John T. Heck, Elmhurst, and Leo J. Du Mais and
Curtis O. Talbot, Chicago, Ill., assignors to Da-
Lite Screen Company, Inc., Chicago, Ill., a cor-
poration of Illinois

Application July 3, 1947, Serial No. 140,092

Term of patent 14 years

(Cl. D61—1)

To all whom it may concern:

Be it known that we, John T. Heck, residing at Elmhurst, in the county of Du Page and State of Illinois, Leo J. Du Mais, residing at Chicago, in the county of Cook and State of Illinois, and Curtis O. Talbot, residing at Chicago, in the county of Cook and State of Illinois, all citizens of the United States of America, have invented a new, original, and ornamental Design for Portable Picture Screen Base, of which the following is a specification, reference being had to the accompanying drawing, forming part thereof.

Figure 1 is a perspective view of a portable picture screen base, showing our new design.

Figure 2 is a side elevational view of the central cross member taken on the line 2—2 of Fig. 1, parts being shown in cross section.

Figure 3 is an end elevational view of the central cross member taken from the left hand side of Fig. 2.

Figure 4 is a side elevational view of the end cross members shown in Fig. 1.

We claim:

The ornamental design for a portable picture screen base, as shown.
